WEATHER KIT FOR MILITARY VEHICLES
 Paul A. Fair, Fallston, Md., and Howard I. Huff, Mickleton, N.J., assignors to the United States of America as represented by the Secretary of the Army

Filed Oct. 21, 1963, Ser. No. 317,848

11 Claims. (Cl. 89—36)

(Granted under Title 35, U.S. Code (1952), sec. 266)

The invention described herein, if patented, may be manufactured and used by or for the Government for governmental purposes, without the payment to us of any royalty thereon.

This invention relates to means to provide one or more seats and a shelter for riders on normally seatless and topless vehicles. The invention is particularly applicable to military vehicles and an important usage of the invention is on self propelled weapons. Current self propelled weapons while they may provide forward enclosures for the driver and observer or gun captain make no provision for the gun crew who ride atop the vehicle in exposed relation to the elements or on a separate truck. It is essential at times that the crew be with the vehicle to insure the weapon being placed into action with a minimum of delay in an emergency. The nature of a self propelled weapon, such as a howitzer, requires that it be exposed on top of the vehicle with ammunition available in top opening magazines so as to be readily available. Any usual collapsible top shelter if collapsing forwardly would either obscure the driver's vision or that of the gun pointer. In like manner if such a top were rearwardly collapsible it would interfere with the loading of the gun and/or might be in the way of the recoil of the piece.

With the foregoing in view, it is an object of the invention to provide a novel shelter means for one or more crew members or riders, which shelter is adopted to have an operative position on top of the vehicle and a collapsed position alongside of the vehicle.

A further object is to provide a shelter comprising a flat base, means mounting the collapsible shelter on the base, hinges hinging the base to the vehicle for movement from an operative position atop the vehicle to an inoperative position alongside the vehicle.

A further object is to provide in combination with such a shelter, novel seat means on said base for one or more riders or crew members.

A further object is to provide with such a combination a novel back rest which is foldable to an inoperative position when the assembly is moved to its non-use position.

Other objects and advantages reside in the specific structure of the invention, the structure of the several elements thereof, combinations and sub-combinations of such elements with each other and/or with the vehicle mounting the same, all of which will be readily apparent to those skilled in the art upon reference to the attached drawing and to the following specification wherein the invention is shown, described and claimed.

In the drawing:

FIGURE 1 is a perspective view of a vehicle having the invention applied thereto, the parts being shown in the shelter-providing positions;

FIGURE 2 is a view like FIGURE 1 but showing the parts in inoperative positions;

FIGURE 3 is an enlarged fragmentary elevational view of a preferred form of seating arrangement parts being shown in section;

FIGURE 4 is a top plan view of FIGURE 3 parts being omitted and parts being shown in section;

FIGURE 5 is an enlarged cross sectional view showing a catch for securing a shelter in the operative position;

2

FIGURE 6 is a fragmentary perspective view and shows one of the hinge means for securing the base to the vehicle;

FIGURE 7 is a cross sectional view showing means for securing the base in the operative position;

FIGURE 8 is a fragmentary vertical sectional view taken substantially on the plane of the line 8—8 of FIGURE 9;

FIGURE 9 is a transverse vertical sectional view taken substantially on the plane of the line 9—9 of FIGURE 8; and

FIGURES 10 and 11 are fragmentary vertical sectional views showing details of a shelter, the same being shown in the raised position.

Referring specifically to the drawing, wherein like reference characters designate like parts in all views, and referring at first to FIGURES 1 and 2, 12 designates any suitable vehicle such as a self-propelled weapon having any suitable body 13, running gear 14 and mounting thereon any suitable weapon such as the field piece 15. The latter includes one or more hydraulic recoil cylinders 16 and the top of body 13 may be formed with a raised engine cover fairing 17 and one or more ammunition magazines or wells 18. In the species illustrated, the invention comprises a pair of shelters 19 which, when in use, are located atop the vehicle body 13 on opposite sides of the piece 15. The shelters 19 are substantially identical so it will suffice to describe but one of them. Each cover is formed of two pieces, a smaller rear section 20 and a larger front section 21. Each section 20, 21 is formed mainly of opaque water impermeable material such as coated cloth. The front sections 21 also include rear, side and front windows 22, 23 and 24 respectively of any suitable flexible transparent plastic material. The front and rear sections 21, 20 are supported by bows 25 of any suitable tubular metal. The ends of the legs are pivotally connected in a manner readily understood to side plates 26 fixed to a base frame 27, to be described later. As best seen in FIGURE 5 those bows 25^a and 25^b which abut when sections 20, 21 are raised can be connected together by any suitable spring catch 28 mounted on bow 25^a. Catch 28 may have a cam surface 29 which engages a striker 30 carried by bow 25^b so as to be automatically tripped as the bows 25^a and 25^b come together. Release is achieved by manually withdrawing latch 28 by its finger-piece 31. Obviously, many other means for readily releasably connecting together bows 25^a and 25^b will suggest themselves to those skilled in the art.

The side plates 26 on which bows 25 are pivoted are fixed in any suitable manner to the upright flanges of metal angles forming the frame 27. As best seen in FIGURES 10 and 11 such frame 27 is suitably shaped to fit over the engine cover fairing 17 and the inside legs 25^c of the bows of the forward shelter section 21 are shaped to avoid the recoil cylinder 16 of the weapon 15.

Two seats 32 and 33, best seen in FIGURES 3 and 4, are mounted on frame 27. In the embodiment illustrated, seat 32 faces forwardly and seat 33 faces rearwardly. The seats 32 and 33 are mounted on leaf springs 34 and 35 respectively. The remote ends 36 and 37 of the springs are formed as bearings and are pivoted on front and rear journal portions of cross pieces 38 and 39 which are fixed across frame 27. Fixed stops 40, 41 on cross pieces 38, 39 retain the bearings 36, 37 in central positions on the journal portions.

The adjacent ends of springs 34, 35 are likewise formed as bearings 42, 43 and are pivoted on journals 44, 45 which are fixed in the lower ends of pairs of links 46, 47. The upper ends of links 46, 47 are overlapped and pivotally mounted on a cross shaft 48 which is fixed between

two uprights 49 which are fixed to a central cross piece 50. Cross piece 50 is fixed to frame 27 and extends across the same. Thus, as springs 34, 35 are flexed the lower ends of links 46, 47 swing back and forth in a manner readily understood to provide resilient mounts for the seats.

As best seen in FIGURE 3, a common backrest 51 is provided for the seats 32, 33. Such backrest 51, may comprise front and rear cushions 52, 53 which are fixed atop an upright 54. The lower end of upright 54 is formed as a bearing 55, FIGURE 9, which is journaled on a shaft 56 which extends between the uprights 49 aforesaid above the shaft 48. Any suitable spring loaded detent 57 may be used to readily releasably secure upright 54 in the back rest providing position. For instance, in FIGURE 8, detent 57 seats in spaced sockets 59 in shaft 48 under the influence of spring 58, which has one end fixed to bearing 55 and the other end secured to the detent in any well known manner.

As best seen in broken lines in FIGURES 3 and 8 release of the detent 57 permits the back rest 51 to be folded forwardly into seat 32.

The frame 27, when in the operative position is horizontally disposed on top of the body 13. Hinges 60 connect the outside of each frame 27 to the body 13 at the outermost limits of the latter. Laterally inwardly extending bifurcated ears 65, see FIGURES 4 and 7, are fixed to the inside of each frame 27. These are engaged by bolts 66 which are pivoted to the top of body 13. Wing nuts 67 engage the ears 65 to secure frame 27 in the operative position.

As best seen in FIGURE 6, each hinge 60 is a double hinge. That is, it includes two laterally spaced and parallel pivots. Thus, one leaf 61 is vertically disposed and fixed to the outside of body 13 at its intersection with top wall. The upper edge of leaf 61 is hinged as at 62 to the lower edge of a second leaf 63, the upper edge of which is hinged in turn as at 64 to the upper edge of the frame 27. The purpose of this arrangement will be apparent later.

In operation, with the parts in the operative positions of FIGURE 1, the riders release the latches 28 and lower the shelter sections 20, 21 to the positions shown at the left in FIGURE 2. Then the detent 57 is released to permit the seat back or back rest 51 to be swung to the inoperative position shown in broken lines in FIGURES 3 and 8. The wing nuts 67 are now loosened and the bolts 66 are swung out of engagement with the ears or lugs 65. Each assembly of base 27, collapsed shelters 20, 21, seats 32, 33 and folded back rest 51 is now swung on hinges 60 through 270° until it hangs in the vertical inoperative position shown at the right in FIGURE 2. The double hinge 60 is now extended to the broken line position of FIGURE 6 whereby the collapsed assembly lies flatly alongside of body 13, which is a position which could not be achieved by an ordinary single hinge. Note too, that the weight of the assembly will cause it to retain this position although suitable readily releasable fasteners, not shown, can be used if desired. For instance, pivoted bolts like 66 could be attached to the sides of body 13 and engaged with ears 65 to secure the assemblies in the inoperative positions.

Another feature of the invention is that when the assemblies are secured in the inoperative positions, the folded seat back 51 and the collapsed shelter sections 20, 21 are pressed against the sides of body 13 whereby there is no need to secure them in the folded or collapsed positions. This feature saves considerable time in both erecting and inactivating the assembly.

It should be noted also that the assemblies can be activated and inactivated without the use of tools, does not require special skills and can be done by personnel under blackout conditions and while wearing protective hand coverings. Also, the assemblies may be readily applied

to standard vehicles with no substantial modification of the latter except for the addition of the hinges 60 and fasteners as 66.

Moreover, while there has been shown and described what is now thought to be a preferred embodiment of the invention, it should be understood that the same is susceptible of other forms and expressions. Therefore, we do not consider the invention to be limited to the exact structure shown and described hereinabove but only as hereinafter claimed.

We claim:

1. The combination with a vehicle, and a weapon mounted on said vehicle, of at least one rider shelter, said shelter comprising an assembly including a flat base, at least one rider seat and a rider shelter, mounting means mounting said shelter assembly on top of said vehicle at one side of said weapon, means mounting said seat atop said base, said seat including a seat back, means mounting said seat back for movement from an upright back rest-providing position to a relatively flat inactive position, said shelter including means for collapsing the same from a raised shelter-providing position covering said base and seat to a relatively flat collapsed position, and said base assembly with said seat-back and shelter in said inactive and collapsed positions respectively being movable on said mounting means from an operative horizontal position atop said vehicle to an inoperative vertical position alongside said vehicle.

2. The combination with a vehicle having a weapon mounted thereon; of at least one rider shelter, said shelter comprising an assembly including a flat rigid base, at least one rider seat and a rider shelter, hinge means mounting said base on said vehicle at one side of said weapon, means mounting said seat atop said base, said seat including a seat back, means mounting said seat back for movement from an upright back rest-providing position to a relatively flat inactive position, means mounting said shelter atop said base, said shelter including means for collapsing the same from a raised shelter providing position covering said base and seat to a relatively flat collapsed position, and said base assembly with said back rest and shelter in said inactive and collapsed positions respectively being swingable on said hinge means from a horizontal operative position atop said vehicle to a vertical inoperative position alongside said vehicle.

3. The combination with a vehicle having a weapon mounted thereon; of at least one rider shelter, said shelter comprising an assembly including a cover, a flat rigid base, a pair of rider seats, means mounting said seats on said base in longitudinally aligned back-to-back relation, a common back rest for said seats, means mounting said back rest on said base for pivotal movement from an upright back rest providing position to a relatively flat inactive position, means mounting said cover atop said base, said cover including means for collapsing the same from a raised shelter-providing position to a relatively flat collapsed position, hinge means mounting said base on said vehicle, and said assembly with said back rest and cover in said inactive and collapsed positions respectively being swingable on said hinge means from a horizontal operative position atop said vehicle alongside said weapon to a vertical inoperative position alongside said vehicle.

4. The combination with a vehicle having a weapon mounted thereon; of at least one rider shelter, said shelter including a roof portion formed to collapse from a raised shelter providing position to a substantially flat collapsed position, means mounting said shelter on said vehicle at one side of said weapon, and means for moving said collapsed shelter from a substantially horizontal position atop said vehicle to a substantially vertical inoperative position alongside said vehicle.

5. The combination with a vehicle having a weapon mounted thereon; of at least one rider shelter, said shelter being formed to be collapsed from a raised shelter-providing position to a substantially flat collapsed position,

hinge means mounting said shelter atop said vehicle at one side of said weapon, and said shelter being swingable on said hinge means from a substantially horizontal operative position atop said vehicle to a substantially vertical inoperative position alongside of said vehicle.

6. The combination with a vehicle having a weapon mounted thereon; of at least one rider shelter assembly, said assembly comprising a pair of seats and a roof portion, means mounting said seats on said vehicle at one side of said weapon in longitudinally aligned relation, said roof portion being formed to be folded from a raised roof-providing position covering said seats to a substantially flat collapsed position, and means for moving said assembly with said roof portion in said collapsed position from a substantially horizontal position atop said vehicle to a substantially vertical inoperative position alongside of said vehicle.

7. The combination with a vehicle having a weapon mounted thereon; of at least one rider shelter, said shelter including a flat base, a collapsible roof portion on said base, said roof portion being adapted to be collapsed from a raised shelter-providing position to a substantially flat collapsed position, means mounting said shelter atop said vehicle alongside said weapon in a substantially horizontal operative position, and said last means including means for positioning said base and shelter in a substantially vertical inoperative position alongside said vehicle, and said roof portion being disposed between said base and said vehicle when said shelter is in said inoperative position.

8. The combination with a vehicle having a weapon mounted thereon; of at least one rider shelter, said shelter including a flat base, a collapsible roof portion on said base, said roof portion being adapted to be collapsed from a raised shelter-providing position to a substantially flat collapsed position, means mounting said shelter atop said vehicle alongside said weapon in a substantially horizontal operative position, and said last means including

double hinge means hinging one side of said base to said vehicle, said double hinge means comprising means for moving said base and collapsed roof portion to a substantially vertical inoperative position flatly alongside said vehicle with said roof portion positioned between said base and vehicle.

9. The combination of claim 2, wherein said hinge means comprises double hinge means whereby said seats and collapsed shelter are positioned flatly against said vehicle when said assembly is in said inoperative position.

10. The combination with a vehicle having a weapon mounted thereon; of at least one rider shelter, said shelter comprising an assembly including a collapsible cover, a flat rigid base, a pair of rider seats, a leaf spring for each seat, means mounting said seats centrally of said springs, said seats being arranged in longitudinally aligned back-to-back relation, said seats having adjacent and remote ends formed as bearings, fixed means including journal portions extending across said base, said remote ends of said springs being journalled on said journal portions, movable journal means pivotally engaged with said bearings of a said adjacent ends of said springs, means mounting said movable journals for fore and aft movement relative to said base, means mounting said cover atop said base, said cover including means for collapsing the same from a raised shelter-providing position to a relatively flat collapsed position, hinge means mounting said base on said vehicle, and said assembly with said cover in said collapsed position being swingable on said hinge means from a horizontal operative position atop said vehicle to a vertical inoperative position alongside said vehicle.

11. The combination of claim 10, there being a common back rest for said seats, means mounting said back rest on said base for pivotal movement from an upright back rest providing position to a relative flat inactive position.
